UNITED STATES PATENT OFFICE.

FRANK STEWART, OF CHICAGO, ILLINOIS, ASSIGNOR TO THE STOCKHAM MANUFACTURING COMPANY, OF SAME PLACE.

DESIGN FOR A CLOCK-FRAME.

SPECIFICATION forming part of Design No. 30,608, dated April 25, 1899.

Application filed March 24, 1899. Serial No. 710,377. Term of patent 7 years.

To all whom it may concern:

Be it known that I, FRANK STEWART, a citizen of the United States, residing at Chicago, in the county of Cook and State of Illinois, 5 have invented and produced a new and original Design for a Clock-Frame, of which the following is a specification.

The accompanying drawing shows my design of a clock-frame by a view in front elevation.

As shown in the accompanying drawing, the leading or material feature of my design consists in the figure of an anchor A, intersected by a circular wreath B. At the opening in the wreath is presented a clock-face C, and the anchor rests in inclined position on a base D, shown longitudinally curved. The wreath is represented as fastened by a ribbon a, containing a bow a', to the anchor-

ring, whence the ribbon passes about one arm 20 of the cross-head A' of the anchor, and from the wreath below the opposite arm of the cross-head there projects a bunch of leaves b, below which is shown rope c, a section thereof also showing under the anchor. A piece of 25 drapery d, ornamented with a rosette f, extends from a side of the wreath over and depends from a fluke of the anchor and is lost in a tassel g, resting on the base D.

Having described my invention, what I 30 claim as new, and desire to secure by Letters Patent, is—

The design for a clock-frame, as herein shown and described.

FRANK STEWART.
